UNITED STATES PATENT OFFICE.

HOWARD H. WILHELM, OF JEFFERSON CITY, MISSOURI.

DISPENSING CONTAINER.

Application filed May 16, 1927. Serial No. 191,905.

This invention relates to new and useful improvements in containers of the dispensing variety and aims to provide a highly novel, simple, and inexpensive device of this character wherein indicating slugs, markers or the like used in chance controlled games may be singly dispensed to the various players of the game after which the proper moves as directed by the lug or marker may be made.

In carrying out my invention there is provided a container that generally includes a box having slideable means for receiving a single slug or marker within the box from whence it may be delivered by pulling outwardly upon the slide and then removing the slug therefrom.

In the drawing wherein like reference characters indicate corresponding parts throughout the several views:

20 Figure 1 is a top plan view of the dispensing container.

Figure 2 is a front end elevation.

Figure 3 is a detail longitudinal section, and

25 Figure 4 is a bottom plan view, the bottom wall thereof being removed for more clearly disclosing the construction of the dispensing slide member.

Figure 5 is a perspective view of a disc or 30 slug used in the dispensing container.

Now having particular reference to the drawing my novel dispensing container consists of a box 5 preferably of square or rectangular configuration having a false bottom wall 6 in spaced parallel relation with the main bottom wall as indicated in Figure 3. This false bottom wall 6 is formed adjacent its forward end and at its center with a circular opening 7, while arranged upon the 35 front wall of the box directly above this opening 7 is a deflection wall 8 preferably of segmental circular formation as indicated in Figure 4.

The top wall of the box is formed directly 40 above the opening 7 of the false bottom wall 6 with an entrance slot 9, the purpose of the member 8 being to deflect the articles from the opening 7 that are delivered to the box to the slot 9.

45 The forward wall of the box 5 directly in front of the opening 7 in the false bottom wall 6 is provided with a slot 10, while slidable therethrough and into the box is a delivery

plate 11 of relatively narrow formation and formed at its inner end with a cross strip 12, 55 the ends of which will strike against blocks 13-13 between the main and false walls of the box 5 at opposite sides of the slot 10 in the forward wall thereof for preventing the entire removal of the delivery member from 60 said box.

The top face of this delivery member 11 is formed with a pocket 14 for registry with the opening 7 in the false wall 6 when the delivery member is extended rearwardly to its 65 limit of movement as in Figure 3, the length of the delivery member being such that the outer end thereof will at all times project through the slot 10 in the forward wall of the box 5 so that it may be grasped in the fingers 70 of the operator.

75 Preferably circular slugs or discs A of the character disclosed in Figure 5 are to be arranged within this box, the top or bottom or both faces of the slug or disc having indicating characters or wording thereon representative of certain moves to be made by the individual players in a game of ten. Obviously the box 5 carries a number of these slugs or discs and by shaking the box one of the same 80 will be caused to pass through the opening 7 in the false wall 6 to drop into the pocket 14 into the delivery slide 11, after which the same may be withdrawn from the box by pulling the slide forwardly, and then by returning 85 the slide the operation may be repeated.

It will thus be seen that I have provided a highly novel, simple, and inexpensive dispensing container that is well adapted for all the purposes heretofore designated, even 90 though I have herein shown and described the invention as consisting of certain detail structural elements it is nevertheless to be understood that some changes may be made therein without affecting the spirit and scope of 95 the appended claim.

Having thus described the invention, what I claim is:—

In a dispensing container of the character described, a closed box having an article entrance opening within the top wall thereof, a 100 false bottom wall within the box in spaced relation with the main bottom wall thereof, one end wall of the box being provided with an opening between said false and main bottom wall, said false wall being provided with 105

an opening through which the articles within the box may pass, and a T-shaped slide member mounted for sliding engagement between the false and bottom walls of the box,
5 the outer end of the slide member at all times projecting through the opening in the box, and being provided at its top side with a pocket for registry with the opening in the

false wall when the member is slid inwardly so that the articles passing through the opening in the false wall may drop therein and be removed from the box by moving the slide member in an outward direction. 10

In testimony whereof I affix my signature.

HOWARD H. WILHELM.
